HOT WATER HEATER

Harvey R. Karlen, Chicago, Ill., assignor to Cory Corporation, a corporation of Delaware

Continuation of application Serial No. 590,852, June 12, 1956. This application January 8, 1958, Serial No. 707,832

6 Claims. (Cl. 219—38)

This invention relates to a hot water heater and in particular to a hot water heater of the open-to-atmosphere type having means for preventing undesired dripping therefrom.

This application is a continuation of my co-pending application Serial No. 590,852, filed June 12, 1956, for a Hot Water Heater.

In the open-to-atmosphere type of liquid heater, liquid is admitted to a closed tank from a suitable valved supply. The liquid is discharged from the tank through an open outlet normally disposed adjacent the top of the tank, and, as it is the supply means which is controlled to stop the flow, the liquid continues to run from the tank until the level of the liquid in the tank is below the level of the outlet. Because liquids such as water expand upon being heated, a serious problem arises in the presently known liquid heaters, namely, upon the heating of the liquid in the tank, the volume thereof increases causing the level to rise above the bottom of the outlet and liquid to drip therefrom.

The principal object of this invention is to provide a liquid heater of the open-to-atmosphere type having new and improved automatic means for preventing dripping of the liquid from the tank outlet.

A further object is to provide such a liquid heater adapted for use in beverage brewers wherein discharge of liquid from the heater tank may be impeded, as by a beverage charge.

Another object is to provide such a liquid heater wherein the means for preventing dripping from the outlet comprises an expansion tank extending to below the level of the outlet with a passage intercommunicating between the interior of the expansion tank and the interior of the main liquid tank below the level of the outlet and with suitable heating means extending to within the expansion tank for vaporizing the liquid therein when flow through the main tank is effected.

A still further object of the invention is to provide such a liquid heater having a vacuum breaker associated with the outlet to allow passages of vapors and gases from and into the main tank and arranged to limit the flow of liquid from the tank to through only the desired outlet duct.

Other features and advantages of the invention will be apparent from the following description taken in connection with the accompanying drawings wherein:

Figure 1 is an elevational view of a liquid heater embodying the invention, with portions thereof shown in diametric section and with the electrical wiring thereof shown diagrammatically; and

Figure 2 is a fragmentary view of the liquid heater of Figure 1, with the elements thereof in the flow-shut-off condition.

In the exemplary embodiment of the invention as disclosed in the drawings, a liquid heater is shown to comprise a tank 10 having a top 11 provided with an open-to-atmosphere outlet generally designated 12. Secured to top 11 to extend downwardly into tank 10 to below

2

the outlet 12 is an expansion tank or enclosure generally designated 13 having therewithin a heating means 14. A passage or opening 13a is provided in the bottom of tank 13 permitting free flow of liquid between the interior of tank 10 and the interior of expansion tank 13.

Preferably adjacent the bottom of tank 10 and extending to interiorly thereof are a liquid supply inlet 15, a heating means 16, and a thermostat means 17 for automatically controlling the heating means 16. To control inlet 15 a suitable valve means 15a is provided. In the preferred embodiment, heating means 14 and valve means 15a are functionally correlated so that heating means 14 is energized only when the valve is open and liquid is caused to be discharged from outlet 12, the heating capacity of means 14 being sufficient to vaporize the liquid in tank 13 and force liquid from tank 13 into main tank 10 during this discharge. Upon closing of valve 15a, the deenergization of heating means 14 permits a cooling and condensation of the vapor within tank 13 with the resultant below atmospheric pressure produced therein inducing a flow of the liquid in tank 10 back into tank 13, with the volume of the liquid thus being drawn from tank 10 causing a lowering of the level of the liquid in tank 10 to substantially below outlet 12.

Top 11 is preferably secured across the upper end of tank 10 by suitable sealing securing means 11a. While expansion tank 13 may be disposed interiorly or exteriorly of tank 10 for purposes of illustrating the invention, it is shown fixedly secured to the underside of top 11 to depend into the upper portion of the tank 10 with opening 13a being provided in the bottom thereof. In the illustrative embodiment of the drawings, heating means 14 comprises an electrically energized heating rod having its ends brought through the top of tank 13 and top 11 for electrical connection thereof to a suitable electrical supply 19.

Outlet 12 includes a T-shaped connection 12a having one leg secured to top 11 to have communication through an opening 11b in top 11 to the interior of tank 10. The stem portion of connection 12a is arranged to receive a suitable connecting duct 20 for conducting the heated liquid such as water to a desired device, such as a coffee brewing cartridge (not shown). A vacuum breaker 12b is secured to the other leg of connection 12a and operates to allow air to pass into the upper portion of tank 10 when liquid is being withdrawn from tank 10 into expansion tank 13. Further, the vacuum breaker is arranged to allow the discharge of vapors such as steam from tank 10 thereby functioning as a safety device should thermostat 17 improperly allow heating means 16 to be continuously energized with flow through duct 20 being prevented. Breaker 12b is further arranged to be closed by the action of liquid flowing from tank 10 and outwardly through duct 20 thereby precluding undesired loss of liquid through the breaker. The illustrated embodiment of vacuum breaker 12 comprises a tubular member connected at one end to have communication through connection 12a with the interior of tank 10 and including a movable ball 12c freely resting on a pin 12d to allow the passage of gases such as air or steam therearound but movable by the action of liquid in connection 12a to be raised to a position wherein it closes off inlet passage 12e of the vacuum breaker.

Valve 15a preferably is of the electric-solenoid type and is arranged to be connected in parallel with electrical heating means 14 so that heating means 14 is energized only when the valve is open and liquid is passing through tank 10. Any suitable means for controlling the energization of valve 15a and heating means 14 may be used, a switch 15b being shown for this purpose.

Heating means 16 may be connected as shown to electric supply 19 through thermostat 17 so that the tem-

perature of the liquid in tank 10 is maintained at the desired point at all times. Where the liquid heater is used in a coffee brewer, for example, this temperature would be approximately 190° F.

The operation of my liquid heater may be best seen by first referring to Fig. 1 which shows the device in the hot-water-discharging condition. Thus, switch 15b is closed to open valve 15a and energize heating means 14. The opening of valve 15a causes water to enter the bottom of tank 10 from inlet 15, thereby forcing the previously heated water in the upper portion of the tank outwardly through outlet 12 and duct 20. The heat generated in heating means 14 causes previously heated water in enclosure 13 substantially immediately to reach the boiling point with the resultant pressure increase in the enclosure being sufficient to overcome the pressure of the liquid in tank 10 and force all liquid outwardly from the enclosure and into the main body of liquid in tank 10. As heating means 14 is continuously energized during this phase of the operation, sufficient vaporization is maintained at all times to maintain the desired removal of liquid from enclosure or tank 13. Any steam or similar vapor passed into the liquid in tank 10 is generally assimilated by the body of liquid therein so that by the time the liquid reaches outlet opening 11b the gaseous phase has disappeared. As only a relatively small body of liquid is originally within tank 13, the assimilation of the vaporized liquid therefrom into the main body of liquid in tank 10 does not appreciably raise the temperature of the liquid being passed outwardly from outlet 12.

Turning now more particularly to Fig. 2, the functioning of my device upon the closing of valve 15a may be seen. Thus, when the inlet valve is closed discontinuing flow of liquid into tank 10, flow from outlet 12 stops, 35 the level of liquid in connection 12a falling to the bottom of duct 20. If this level were allowed to be maintained, however, the subsequent heating by heating means 16 of the recently inducted, relatively cool water from inlet 15 into tank 10 would cause, by the resulting expansion of the water in tank 10, the level of the water at outlet 12 to rise slowly and effect a dripping thereof from duct 20. However, as seen in Fig. 2, when heating means 14 is deenergized concurrently with the closing of valve 15a, the vapor within expansion tank 13 condenses thereby forming a vacuum in tank 13 and inducing a flow of liquid from tank 10 backwardly into expansion tank 13 until the level of liquid in tank 10 is substantially below outlet 12. By making the capacity of expansion tank 13 sufficiently large, the total expansion of the liquid in tank 10 as caused by the subsequent heating thereof may be accommodated with the level of the liquid in tank 10 being maintained below the outlet. Should duct 20 for any reason be closed, vacuum breaker 12b allows the entry of air through connection 12a into the top portion of tank 10 to allow unimpeded suction of the liquid into tank 13.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A drip-proof liquid heater comprising: a closed tank having a top; an open outlet through the tank at the top; means for effecting liquid flow into the tank; means for heating liquid in the tank; and means for lowering the liquid level in the tank to below the outlet when liquid flow therethrough is discontinued, including an enclosure, passage means communicating between the interior of the enclosure and the interior of the tank below said outlet to allow a quantity of liquid to be disposed with said enclosure, and heating means associated with said enclosure operable concurrently with said means for

effecting liquid flow to vaporize the liquid in said enclosure during liquid flow through the tank, and to be deenergized upon discontinuance of flow causing a pressure to exist in said enclosure which is lower than the pressure in the tank at the passage means to induce flow of liquid thereinto from the liquid in the tank.

2. A drip-proof liquid heater comprising: a closed tank having a top; an open outlet through the tank at the top; means for effecting liquid flow into the tank; means for heating liquid in the tank; and means for lowering the liquid level in the tank to below the outlet when liquid flow therethrough is discontinued, including an enclosure in said tank and having an opening communicating with the interior of the tank below said outlet to allow a quantity of liquid to be disposed within said enclosure, and heating means associated with said enclosure operable concurrently with said means for effecting liquid flow to vaporize the liquid in said enclosure during liquid flow through the tank, and to be deenergized upon discontinuance of flow causing a pressure to exist in said enclosure which is lower than the pressure in the tank at the opening to induce flow of liquid thereinto from the liquid in the tank.

3. A drip-proof liquid heater comprising: a closed tank having a top; an open-to-atmosphere outlet through said top; valve means operable to permit gas flow in and out of the top portion of said tank but arranged to be closed whenever liquid is flowing from said tank through said outlet; means for effecting liquid flow into the tank; means for heating liquid in the tank; and means for lowering the liquid level in the tank to below the outlet when liquid flow therethrough is discontinued, including an enclosure, passage means communicating between the interior of the enclosure and the interior of the tank below said outlet to allow a quantity of liquid to be disposed within said enclosure, and heating means associated with said enclosure operable concurrently with said means for effecting liquid flow to vaporize the liquid in said enclosure during liquid flow through the tank, and to be deenergized upon discontinuance of flow causing a pressure to exist in said enclosure which is lower than the pressure in the tank at the passage means to induce flow of liquid thereinto from the liquid in the tank.

4. A drip-proof liquid heater comprising: a closed tank having a top; an open outlet through the tank at the top; means for effecting liquid flow into the tank including an electrically operated, flow controlling valve; means for heating liquid in the tank; and means for lowering the liquid level in the tank to below the outlet when liquid flow therethrough is discontinued, including an enclosure, passage means communicating between the interior of the enclosure and the interior of the tank below said outlet to cause a quantity of liquid to be disposed within said enclosure, and electric heating means in said enclosure arranged to be energized concurrently with the opening of said valve to vaporize the liquid in said enclosure during liquid flow through the tank and to be deenergized upon closing of said valve causing a pressure to develop in said enclosure which is lower than the pressure in the tank at the passage means to induce flow of liquid thereinto from the liquid in the tank.

5. A drip-proof liquid heater comprising: a tank having a top; an open outlet through the tank at the top; an inlet to the tank; means for controlling flow of liquid through said inlet into the tank whereby the liquid may flow through the tank and from said outlet; means for heating liquid in the tank; and means for lowering the liquid level in the tank to below the outlet subsequent to a discontinuation of liquid flow through the tank, including means for vaporizing at an elevated temperature a portion of the liquid between the inlet and outlet during liquid flow through the tank, said means permitting the vaporized liquid to cool and be reduced in volume subsequent to a discontinuation of the flow of liquid through the tank.

6. A drip-proof liquid heater means comprising: a tank having a top; an open outlet through the tank at the top; an inlet to the tank; means for controlling flow of liquid through said inlet into the tank whereby the liquid may flow through the tank and from said outlet; and means for lowering the liquid level in the tank to below the outlet subsequent to a discontinuation of liquid flow through the tank, including a sealed enclosure communicating with the interior of the tank below the outlet to receive liquid from the tank and having associated therewith means heating and resultingly expanding the liquid in said enclosure during liquid flow through the tank, said means permitting the expanded liquid to

cool in said enclosure and contract to produce a reduced pressure in said enclosure subsequent to a discontinuation of the flow of liquid through the tank.
